UNITED STATES PATENT OFFICE.

ELI LIEBER, OF KNOXVILLE, TENNESSEE.

BALLOT-CABINET.

1,277,959.

Specification of Letters Patent. Patented Sept. 3, 1918.

Application filed November 16, 1917. Serial No. 202,398.

To all whom it may concern:

Be it known that I, ELI LIEBER, a citizen of the United States, residing at Knoxville, in the county of Knox and State of Tennessee, have invented new and useful Improvements in Ballot-Cabinets, of which the following is a specification.

This invention relates to new and useful improvements in voting machines, and the 10 principal object of the invention is to provide a cabinet provided with means by which voting by white and black balls may be carried out.

Another object of the invention is to provide the drawer with a plurality of openings in its top and with a plurality of sliding drawers therein with means connecting each opening with one of the drawers.

Another object of the invention is to provide a device of this character which is simple and durable in construction, reliable and efficient in operation and one which can be manufactured and placed upon the market at a minimum cost.

25 The invention also consists in certain other features of construction and in the combination and arrangement of the several parts, to be hereinafter fully described, illustrated in the accompanying drawings 30 and specifically pointed out in the appended claim.

In describing my invention in detail, reference will be had to the accompanying drawings wherein like characters denote like 35 or corresponding parts throughout the several views, and in which:—

Figure 1 is a perspective view of my improved cabinet.

Fig. 2 is a longitudinal section.

40 Fig. 3 is a transverse section.

In these figures 1 indicates the cabinet made of any suitable material and of any desired size. In its top said cabinet is provided with a plurality of holes 2 preferably 45 arranged to extend in a transverse line at each end of the cabinet, said holes being of sufficient size to receive the black and white balls usually used in voting in lodges and the like. I locate numerals adjacent the 50 openings as indicated at 3 so as to number said openings and I also provide name plates 4 adjacent said openings to receive the names of the candidates. In the front side of the cabinet I arrange a series of 55 drawers 5, each provided with a numeral 6

and a handle 7. Each drawer extends under one of the openings and it will be seen that the drawers in the upper row are of less length than those in the lower row so that said drawers in the lower row extend under 60 the row of openings adjacent the rear of the cabinet. A tube 8 extends from each opening to a point directly over each drawer so as to lead the ball from said opening into the drawer. It will be seen that each 65 drawer contains a numeral corresponding to the numeral of the opening located thereover.

The candidates' names are placed in the card holders so that the voters will know 70 the names of candidates and they will drop either the white ball or the black ball in the opening adjacent the name accordingly as to whether they are voting for or against him. After the voting is finished the successful candidate will be found by counting 75 the number of white balls in the drawers.

It will be seen that this cabinet provides a speedy and convenient and safe method of conducting two or more secret ballots 80 simultaneously.

It is thought from the foregoing description that the advantages and novel features of my invention will be readily apparent.

I desire it to be understood that I may 85 make slight changes in the construction and in the combination and arrangement of the several parts, provided that such changes fall within the scope of the appended claim.

What I claim is:—

A device of the class described comprising a cabinet having a row of holes in its top adjacent each end thereof, card holding means adjacent each hole, a plurality of sliding drawers in one end of said cabinet, 95 said drawers being arranged in upper and lower rows, the drawers in the upper row being of less length than those in the bottom row so that said upper rows extend under the first row of openings while the 100 lower drawers extend under the second row of openings, tubes extending from the openings in the first row to adjacent the top of the drawers in the upper row, and a second set of tubes extending from the openings 105 in the second row to adjacent the top of the drawers in the lower row.

In testimony whereof I affix my signature.

ELI LIEBER.
